UNITED STATES PATENT OFFICE.

JAMES A. HORNE, OF DENVER, COLORADO.

PROPELLER.

Application filed August 31, 1921. Serial No. 497,105.

To all whom it may concern:

Be it known that I, JAMES A. HORNE, a citizen of the United States, residing at Denver, in the county of Denver and State 5 of Colorado, have invented certain new and useful Improvements in Propellers, of which the following is a specification.

This invention relates to propellers for flying machines, boats, or other similar vehicles, and is capable of use as a fan or ventilator, and in other places. The object of the invention is to provide simple, compact and efficient means whereby the several propeller blades will be rotated 15 about their own axes so as to be feathered as they operate and thereby obtain the maximum power upon their working stroke and minimize resistance upon their return stroke. The invention also has for its object the provision of means whereby the time of feathering or the point at which the blades will 20 be shifted in their movement may be controlled.

The invention is illustrated in the accompanying drawings and will be hereinafter set forth, and in the said drawings,—

Figure 1 is a view, partly in plan and partly in longitudinal section, of one embodiment of my present invention;

Fig. 2 is a side elevation of the same;

Fig. 3 is an elevation showing another form of the invention;

Figs. 4 and 5 are detail views showing variations in the controlling gearing.

Fig. 6 is a view, similar to Fig. 1, showing the application of the form of gearing illustrated in Fig. 5;

Fig. 7 is a detail section through the central group of gears shown in Fig. 6;

Fig. 8 is a detail of one of the pinions;

Fig. 9 is a plan view of means for independently or simultaneously adjusting the propellers at the two sides of a vessel;

Fig. 10 is a detail showing another embodiment of the invention.

In the drawings, a portion of the frame of the vehicle is indicated at 1 and upon the said frame are brackets or standards 2 having bearings 3 at their upper ends to receive and support the controlling shaft or rod 4. Upon the controlling rod or shaft 4 is disposed a housing or tubular frame bar 5 secured at its opposite ends to a hub 6 and to a combined hub and gear casing 7 in any convenient or preferred manner. The main shaft or controlling rod 4 passes through

the hub 6 and the casing 7 and said hub and casing are mounted to rotate about the said controlling rod. Extending radially from the said hub 6 and the casing 7 are 60 tubular frame bars 8 and 9, the outer ends of which are secured respectively in castings forming bearings 10 and combined bearings and gear casings 11, as will be readily understood upon reference to Fig. 1. The 65 frame bars 8 are preferably hollow in order to reduce weight without any loss of strength while the bars 9 are also hollow but are shorter than the frame bars 8 in order to accommodate the larger casings 11. 70 Shafts 12 are disposed rotatably within the frame bars 9 and upon the inner ends of said shafts 12 are secured beveled gears 13 which mesh with a beveled gear 13' secured upon the controlling rod 4 within the gear 75 casing 7, as clearly shown. Upon the outer ends of the shafts 12, within the gear casings 11, are beveled gears 14 which mesh with similar gears 15 on the ends of the propeller blade shafts 16, the said shafts 16 80 being journaled in the casings 11 and in the bearings 10, as clearly shown. Planes or blades 17 are secured to the shafts 16 between the members 10 and 11 and these planes or blades may be of any desired form 85 and dimensions. Disposed loosely upon the controlling rod 4 and secured to the adjacent side of the gear case 7 is the main driving sprocket wheel 18 around which a chain 19 is trained, said chain being actuated by 90 any preferred form of motor. The bearing 3, at the front side of the propelling mechanism, is provided with notches or recesses 20 which are adapted to be engaged by a locking pin 21 mounted in the controlling 95 lever or handle 22 secured upon the adjacent end of the controlling rod 4, the said locking pin 21 being held normally in engagement with one of the recesses or notches 20 by a spring 23 coiled around the pin between the handle 22 and an abutment 24 100 upon the pin.

When power is applied to the driving sprocket 18, the frame consisting of the bars 8 and 9 and the parts connected thereto 105 will be caused to rotate about the rod 4 as an axis and the blades or planes 17 will, consequently, be caused to travel over a circular path, and the resistance offered to the blades or planes by the water, the air, or 110 other medium in which they operate will serve to cause travel of the vehicle, as will

2

be readily understood. The rotation of the frame about the controlling rod 4 will obviously cause the gears 13 to rotate and roll upon the gear 13' secured to the controlling rod, the motion of the said gears 13 being transmitted to and through the shafts 12 to actuate the gears 14 and 15 and thereby effect rotation of the propelling blades or planes about their own axes so that during 10 a portion of the travel of the frame the surfaces of the blades will be presented to the medium in which they are operating, while during another portion, the edges of the blades or planes will be presented to such 15 medium. As a result of this movement of the individual planes or blades relative to the frame, the blades may be caused to generate the maximum power during their travel over the lower portion of their orbit 20 to propel the vehicle forward and during their travel through the upper portion of their orbit will present their edges to the air or water so that the resistance to the return of the blades to the working point will 25 be overcome. The gears 14 and 15 are, in diameter, twice as great as the gears 13 and 13' so that the rotation of the blades or planes about their own axes will be slower than the rotation of the frame about its 30 axis and this reduction of speed will attain the maximum efficiency in the feathering action of the blades. By rocking the controlling rod 4, through the medium of the handle 22, the gears 13 may be rotated independently of the action imparted thereto 35 through the motor and the gearing driven directly thereby so that the point or time of feathering the blades may be changed and this timing of the blades may be accomplished without stopping the motor or the 40 propelling action. This setting of the blades may also be utilized to control the direction of travel of the vehicle or to reverse the same.

45 The gear casings 7 and 11 are obviously hollow to accommodate the gears, and the casing 7 may be provided with any convenient means for admitting oil thereto. The casings 11 are provided with caps 25 50 extending over and covering openings formed in the outer walls of the casings and these openings are large enough to admit the gears 14 and 15 so as to facilitate the assembling of the parts. Of course, the lubricant may be also placed in the casings 55 11 through the same openings.

In the form of the invention shown in Figs. 1 and 2, only two propeller blades are employed, the said blades being disposed at 60 opposite ends of the frame and being at a right angle to each other when the frame is at rest. In Fig. 3, I have shown a form 65 of the invention in which three carrying arms 30 are employed and a blade or plane 31 is mounted at the outer end of each arm,

the driving gearing and the feathering mechanism being the same as in Figs. 1 and 2.

In Fig. 4, I have illustrated an arrangement of the gearing in which the controlling rod 33 carries a pinion 36 corresponding to the pinion 13' in Fig. 1, and the transmission shafts 37 are each equipped at its inner end with a pinion 38 meshing with said pinion 36 but twice as large as said 70 pinion, whereas in the form shown in Fig. 1, the pinions 13 and 13' are all of the same diameter. The pinions 39 and 40 corresponding to the pinions 14 and 15 in Fig. 1 are of equal diameter, but obviously the 80 arrangement shown will reduce the speed of the propeller blade-carrying shaft 41 to the same degree as the arrangement shown in Fig. 1.

In Fig. 5, I have shown the controlling rod 45 equipped with a mutilated gear comprising a semi-circular beveled tooth portion 46 which, in the operation of the machine, will be engaged alternately with the gears 47 upon the inner ends of the transmission 90 shafts 48. The mutilated gear also includes a smooth-faced semi-circular member 49 which has a greater radius than the gear portion 46 and has a rim presenting a flat face 50 to the flat sides 51 on the hubs of the 95 gears 47 as the transmission shafts 48 are successively carried around the controlling rod 45. In this arrangement, during one-half of the revolution of the propeller frame, a blade will be rotating about its 100 own axis and during the other half of the revolution of the frame the blade will be at rest relative to its own axis and will be held at rest by the engagement of the flat hub sides 51 with the flat surface 50 of the 105 member 49. I am thus enabled to set the mechanism so that, during half of the travel of the propeller frame, the blade will be held firmly so as to present its surface to the air or water, while, during the other half 110 of its travel, it will be shifted so that its edge will be presented to the air or water and the angle of the blade relative to the frame will vary so that its edge will be continuously presented to the air or water notwithstanding the shifting of the position of the blade due to the movement of the frame.

In Fig. 10, a double sprocket pinion or a pulley 60 is fixed to the controlling rod or 120 shaft 61 and is connected by chains or belts 62 with the sprockets or pulleys 63 on the propeller shafts, the diameters of the sprockets or pulleys 63 being twice the diameter of the pulley or sprocket 60. 64 designates the frame bars to which motion is imparted from the motor.

In Fig. 9, 70 designates the controlling rods which are disposed within the hollow shafts 71 which are arranged transversely of 130

the vessel and extend to the opposite sides thereof to carry propeller frames 72, being rotated by the sprockets 73 and chains 74 leading from the motor, as will be readily understood. Upon the end of each shaft 70 is a worm gear 75 meshing with a worm 76 on a controlling rod 77, said controlling rods being equipped with handles 78 whereby they may be independently set. Operatively connected with each controlling rod is an indicator 79 whereby the operator may be informed of the point at which each propeller will assume the working position. Between and parallel with the controlling rods 77 is a countershaft 80 which is slidable in its bearings and carries a gear 81 adapted to mesh with the gears 82 on the rods 77. Obviously, if the countershaft be pushed forward so that the gear 81 meshes with the gears 82, the propellers at the two sides of the vehicle may be simultaneously adjusted by the manipulation of either rod 77, and if the gears be out of mesh, as shown, the propellers may be independently adjusted.

In all forms of the invention, the operating gearing, whereby the blades are feathered, is entirely enclosed within the propeller frame so that it is protected against damage from accidental blows and will, therefore, be in operative condition at all times. Moreover, it is direct acting with no lost motion and will attain the desired re-

sults positively and with certainty. The invention is particularly advantageous for application to aeroplanes as the adjustment of the blades may be altered without stopping the motor and they may be set to effect vertical ascent without a preliminary run and, after reaching the desired altitude, instantly changed to cause forward or backward flight.

Having thus described the invention, what is claimed as new is:

1. The combination of a plurality of feathering propellers, a propeller-setting means, and means whereby the propeller-setting means may be caused to set any one or all the propellers.

2. In a propeller, the combination of a rotatable propeller frame, a controlling rod passing through and pivotally supporting said frame, blades mounted at the ends of the frame, means for rotating the controlling rod, means for transmitting movement of the controlling rod to the blades comprising shafts housed in the frame and geared at their outer ends to the blades, beveled gears on the inner ends of said shafts having flat-sided hubs, and a mutilated gear secured on the controlling rod to mesh alternately with said beveled gears, said mutilated gear having a flat-faced rim to engage the flat-sided hubs of the beveled gears alternately.

In testimony whereof I affix my signature.

JAMES A. HORNE. [L. S.]
